UNITED STATES PATENT OFFICE.

HENRY B. THOMAS, OF SEATTLE, WASHINGTON, ASSIGNOR TO THOMAS AND THORNE MFG. COMPANY, OF SEATTLE, WASHINGTON.

COMBINATION SHADE-ROLLER AND CURTAIN-POLE BRACKET.

1,073,372.

Specification of Letters Patent. Patented Sept. 16, 1913.

Application filed February 27, 1912. Serial No. 680,170.

To all whom it may concern:

Be it known that I, HENRY B. THOMAS, a citizen of the United States, residing at Seattle, in the county of King and State of 5 Washington, have invented new and useful Improvements in Combination Shade-Roller and Curtain-Pole Brackets, of which the following is a specification.

The invention relates to brackets, and 10 more particularly to the class of combination curtain, shade and pole supporting brackets.

The primary object of the invention is the provision of a bracket which is formed from 15 a single blank, thereby enabling it to be manufactured at a minimum expense, and that will possess the requisite strength and durability, as well as being capable of ready and easy application to window frames or 20 casements.

Another object of the invention is the provision of a bracket of this character which will be neat and attractive in appearance, and easy to place in position upon a window 25 casement or remove therefrom, and also that will be firm and rigid, when placed in position.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a fragmentary perspective view of the improved shade and curtain hanger or bracket constructed in accordance with the invention, and shown supporting a shade roller and curtain pole. Fig. 2 is a side elevation on an enlarged 35 scale of one of the brackets removed from the window casement. Fig. 3 is a sectional view on the line 3—3 of Fig. 2. Fig. 4 is a top plan view of one of the brackets.

Similar reference characters indicate corresponding parts throughout the several views of the drawings.

Referring to the drawings by numerals, the combination shade and curtain pole holder comprises a pair of complementary 50 brackets A and B, respectively, each being formed from a single blank, comprising a body 5 cut to provide a forwardly projected upwardly curved upper arm 6, and a lower forwardly directed shade roller supporting

wing 7, the same being instruck from one 55 side to provide a reinforcing rib or swell 8 to strengthen the said wing. The wing is formed with a slot 9, and also, spaced therefrom, with an opening 10, the slot being designed to receive the end of the usual stationary rod of a spring shade roller 11, while the opening 10 is adapted to receive the bearing at the rotating end of the said shade roller 11. It is apparent that by providing the wing 8 with both the slot 9 and 65 the opening 10, the shade roller 11 may be reversed in the brackets.

Rising from the free ends of the arms 6 and from the upper edge of the body 5 are spaced vertically disposed front and rear 70 holding lugs 12 and 13, respectively; with either the front or rear holding lugs is adapted to be engaged a drapery pole 14, while adapted to rest upon the arms 6 is an ordinary curtain pole 15.

Formed on each body 5, at the rear edge thereof, are right angularly disposed ears 16, the same containing suitable apertures for receiving screws or nails, whereby the brackets may be fastened to the window casement, 80 so as to be supported thereon in substantially vertical position at the upper end of said casement.

Formed in each body 5 rearwardly of the lug 13 is a recess 17 in which may rest the 85 curtain pole so that the same may lie close to the window frame should it be desired.

What is claimed is:

A bracket comprising a plate having a shade roller engaging wing, base ears integrally formed with the plate at its rear edge and bent at right angles thereto, the said plate being formed with notches in its uppermost edge arranged in spaced relation to each other and of varying sizes with respect to one another, and upstanding lugs integrally formed with the upper edge of the plate and disposed in alternate relation to the notches, one of the notches and one of the lugs being disposed rearwardly of a shade roller with the said wing.

In testimony whereof I affix my signature in presence of two witnesses.

HENRY B. THOMAS.
